UNITED STATES PATENT OFFICE.

CHARLES F. MURRAY, OF EVANSTON, ILLINOIS, ASSIGNOR TO KEYOKE RAILWAY EQUIPMENT COMPANY, OF CHICAGO, ILLINOIS, A CORPORATION OF ILLINOIS.

YOKE-FASTENER.

1,161,876.

Specification of Letters Patent. Patented Nov. 30, 1915.

Application filed February 29, 1912. Serial No. 680,665.

To all whom it may concern:

Be it known that I, CHARLES F. MURRAY, a citizen of the United States, and resident of Evanston, in the county of Cook and State of Illinois, have invented certain new and useful Improvements in Yoke-Fasteners, of which the following is a specification.

My invention relates to draft rigging and has particular reference to a novel connection between the draw-bar and the yoke.

It is well known that the connection between the draw-bar and the yoke is a point of weakness and many constructions have been devised whereby such connection may be strong and rigid and which construction shall eliminate the use of bolts or rivets. It is a common construction to rivet the yoke to the butt end of the draw-bar by means of two rivets. In practice, however, due to side strains, the rivets are very often sheared and the connection broken. One of the prolific causes of delays and accidents is the pulling out of the draw-bar due to a broken connection to the yoke.

It is the object of my present invention to eliminate the possibility of such contingencies and provide a connection which shall be simple, easily applied and removed, which shall eliminate the use of bolts and rivets and which shall absolutely prevent the breaking of the connection between the draw-bar and the yoke.

My invention will be more readily understood by reference to the accompanying drawings, wherein,

Figure 1 is a side elevation partly broken away showing my novel attaching means; Fig. 2 is an enlarged perspective view of the one-piece fastening device; Fig. 3 is a side elevation partly broken away, showing a modification of the construction shown in Figs. 1 and 2; and Fig. 4 is a section on the line 4—4 of Fig. 3.

Referring more particularly to the drawings it will be seen that while I have shown several different modifications, each thereof contemplates coöperation with a draw-bar having a standard shank 10, with upstanding shoulders or abutments 11. Also in the modification shown in Figs. 1 and 3, the yoke 12 is of the ordinary construction having inturned hooks or shoulders 13. In Figs. 1 and 2 the fastening device is a unitary casting or forging 14, having contin-

uous top, bottom and side walls, the two ends being open, the opening through the end nearest the coupler being, however, smaller than the opening through the opposite end. The small opening 15, as shown in Fig. 1, is of a size just sufficient to pass over the enlarged butt end of the draw-bar. This results in the formation of shoulders 16, which coöperate with and securely hook the inturned ends 13 of the yoke. To apply such construction the casting 14 is first slipped over the end of the draw-bar and well up on the shank. The yoke is then applied from the side as is customary, then the retaining device 14 is driven back upon the yoke until it reaches the position of Fig. 1, when a key 17 is driven in place through openings 18 in the casting. Thus it will be seen that the draw-bar and yoke are securely attached and that practically no strain is applied through any pulling or buffing to the key, the whole strain being taken up by the casting.

In the modification shown in Figs. 3 and 4, the draw-bar and yoke remain the same but the casting is formed in two parts 19, 20. These two parts have overlapping sides, each provided with registering slots 21, through which the key 22 may be passed. The advantage in this construction is that the end walls 23 may be longer than by the construction shown in Figs. 1 and 2 and such construction will be found preferable where a tandem gear is employed and a part of the buffing strain is carried by the yoke. Such construction may also be found desirable in combination with a two-part yoke, that is, such a yoke as shown in patent to Murray, No. 1,000,932. By the use of such yoke, all the advantages accruing to the construction shown in such patent may be secured.

Many modifications will undoubtedly suggest themselves to those skilled in the art, but my invention contemplates the employment of a separate, detachable fastening device and any such modifications I consider within the scope of my invention.

I claim:

1. In a device of the class described, the combination of a draw-bar, a yoke, coöperating shoulders and hooks on said draw-bar and yoke, a separate retaining device adapted to clasp said yoke on said draw-bar, said retaining device having inturned hooks co-

operating with the hooks on said yoke, and a key passing through said retaining device and said draw-bar for securing said retaining device in position, substantially 5 as described.

2. In a device of the class described, the combination of a draw-bar, a yoke coöperating shoulders and hooks on said draw-bar and yoke, and a separate two-part clasp 10 having apertured overlapping side flanges, said clasp being adapted to securely hold said yoke in position on said draw-bar, and a key passing through the registering apertures in said clasp and through said draw-bar, substantially as described.

3. In a device of the class described, the

combination of a draw-bar, a yoke, coöperating shoulders and hooks on said draw-bar and yoke, and a separate two-part clasp having apertured overlapping side flanges, 20 said clasp being adapted to securely hold said yoke in position on said draw-bar, inturned hooks on said clasp, said hooks coöperating with the hooks on said yoke, and a key passing through the registering apertures in said clasp and through said draw-bar, substantially as described. 25

CHARLES F. MURRAY.
